(57) **CLAIM**

The ornamental design for a beverage container lid, as shown and described.

DESCRIPTION

FIG. 1 is a top and right side perspective view of a beverage container lid showing my new design.

FIG. 2 is a front side elevational view thereof.

FIG. 3 is a rear side elevational view thereof.

FIG. 4 is a right elevational view thereof.

FIG. 5 is left a elevational view thereof.

FIG. 6 is a top plan view thereof; and,

FIG. 7 is a bottom plan view thereof.

The broken lines represent portions of the beverage container lid that form no part of the claim.
